UNITED STATES PATENT OFFICE

95,921

DESIGN FOR A ROCKING HORSE

Ilonka Karasz Nyland, Brewster, N. Y., assignor to Larkin Company, Inc., Buffalo, N. Y.

Application March 16, 1935, Serial No. 55,902

Term of patent 3½ years

To all whom it may concern:

Be it known that I, Ilonka Karasz Nyland, a citizen of the United States, residing at Gage Hill, Brewster, Putnam County, State of New York, have invented a new, original, and ornamental Design for a Rocking Horse, of which the following is a specification, reference being had to the accompanying drawing, forming a part thereof.

In said drawing:

Fig. 1 is a perspective view of a rocking horse showing my new design.

Fig. 2 is a front elevation thereof.

I claim:

The ornamental design for a rocking horse as shown.

ILONKA KARASZ NYLAND.
